ATTORNEY

UNITED STATES PATENT OFFICE.

FRANK E. MUNI, OF WEST NUTLEY, NEW JERSEY.

DESIGN FOR A MILITARY BADGE.

51,684.

Specification for Design.

Patented Jan. 8, 1918.

Application filed May 18, 1917. Serial No. 169,588. Term of patent 3½ years.

To all whom it may concern:

Be it known that I, FRANK E. MUNI, a citizen of the United States, residing at West Nutley, in the county of Essex and State of New Jersey, have invented a new, original, and ornamental Design for Military Badges, of which the following is a specification, reference being had to the accompanying drawing, forming a part thereof.

The figure is a face view of a military badge showing my new design.

What I claim is:

The ornamental design for a military badge as shown.

FRANK E. MUNI.

Witnesses:

Wm. E. McDougall,
C. W. Mercier.
